UNITED STATES PATENT OFFICE.

HENRY BEESTON, OF PHILADELPHIA, PENNSYLVANIA.

DESIGN FOR A CUSPIDOR.

SPECIFICATION forming part of Design No. 18,259, dated April 17, 1888

Application filed January 17, 1888. Serial No. 261,050. Term of patent 3½ years.

To all whom it may concern:

Be it known that I, HENRY BEESTON, of the city and county of Philadelphia, and State of Pennsylvania, have invented an Improvement 5 in a Design for Cuspidors, of which the following is a specification.

My invention relates to cuspidors, or more particularly to their design or configuration, whereby their beauty, symmetry, and utility 10 are enhanced.

My design is suited more particularly to metallic cuspidors, though it is evident that it may be applied to those made of china, porcelain, or such material.

15 In the drawings, Figure 1 is a side elevation of a cuspidor embodying my design, and Fig. 2 is a plan view of the same.

A is the body, and is of the usual shape. The surface of this body is made to represent 20 beaten or hammered metal, as indicated at D in the drawings.

B is the bowl or bell-mouthed portion, and is made fluted or with slight corrugations converging toward the center, as shown at E.

25 The rim C is preferably turned over into a roll, F.

Looking down upon the cuspidor, we will see

the fluted or corrugated work E radiating from the center opening and bounded by a smooth perimeter, which is bent into a circular roll, F. 30

The essential feature of the design lies in the hammered or beaten work on the body and the fluted or corrugated work on the bell-mouthed or bowl portion. It is evident that the beaten work might extend only part way 35 around the body; hence I do not confine myself to a continuous circle of beaten work on the body.

Having now described my invention, what I claim as new, and desire to secure by Letters 40 Patent, is—

The design for a cuspidor, as herein shown and described, the same consisting of the representation of beaten or hammered work upon the body and the fluted or corrugated ornamentation on the bell-mouthed top or bowl bounded by a smooth perimeter. 45

In testimony of which invention I hereunto set my hand.

HENRY BEESTON.
